UNITED STATES PATENT OFFICE

WALTER BRESLIN, OF NEW YORK, N. Y.

GARTER PAD FORM AND HOOK

Application filed July 29, 1931. Serial No. 553,753.

This invention relates to new and useful improvements in a garter pad form and hook.

The invention has for an object the construction of a garter pad form which is characterized by being of substantially hexagonal shape with a straight side at the top so that inclined sides conveniently connect with the band that extends around one's leg. It is advisable that the garter band be extended at a slight inclination from the horizontal from the front around the leg.

Another one of the objects of this invention is to construct the pad of several layers and to attach a triangular pad on the top of the first mentioned pad, and a hook for the garter band being mounted on the latter pad.

A still further object of this invention is the provision of means for changing the angular position of the triangular pad.

Furthermore, the invention proposes the provision of a garter pad form and hook which is of simple, durable construction, dependable in use and efficient in action and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a fragmentary front elevational view of a garter pad and hook constructed according to this invention.

Fig. 2 is a sectional view taken on the line 40 2—2 of Fig. 1.

Fig. 3 is an elevational view of a pad per se constructed according to a modification of the invention.

Fig. 4 is a fragmentary enlarged sectional view taken on the line 4—4 of Fig. 3.

Fig. 5 is a fragmentary sectional view taken on the line 5—5 of Fig. 3.

The garter pad form and hook, according to this invention, comprises a pad 10 formed of several layers, namely, a bottom layer 11

and a top layer 12 secured together by stitches 13. The top layer is similar to but slightly smaller than the bottom layer. The pad 10 is of substantially hexagonal shape and arranged so as to have a horizontal top side and a horizontal bottom side 14. A garter clamp 15 is secured upon the smaller side 14 and comprises a loop 16 engageable upon a button 17 mounted upon a strip of material 18 which is connected on the straight edge 14. Hose may be clamped between the loop 16 and the button 17.

A triangular pad 19 of isosceles shape is attached along one of its bases upon one of the inclined sides of the hexagonal pad 10. The apex of the isosceles pad terminates in the vicinity of the center of the pad. The isosceles pad is composed of several layers of material, namely, bottom layer 20 and top layer 21 secured together. A hook 22 is mounted upon the apex. A leg band 23 is attached at one end 24 upon the side of the pad 10 which connects with the isosceles pad 19. The band 23 then extends around and terminates in a member 25 capable of being engaged upon the hook 22. It should be noticed that a row of stitches such as 26 serves to hold down the pad 19 on the pad 10.

In the modified form of the device illustrated in Figs. 3 to 5 inclusive, a means has been provided for supporting the pad 19 upon the pad 10 in various angular positions. The intention is that by changing the angular position of the base of the isosceles pad 19 relative to the side upon which the end of the band 23 is attached, adjustments can be made whereby the band engages the leg in a more convenient manner. For this purpose a rivet 27 engages through the upper layer 12 of the pad 10. A bar 28 is secured along the base edge of the pad 19 and is pivotally mounted at one end 29 upon the rivet 27 and at the other end terminates in an eye opening 30. Stitches 31 serve to secure the eye opening down upon the pad so as to hold the isosceles pad 19 in various fixed positions. Dot and dash lines 32 indicate an adjusted position of the bar 28 and necessarily will change the position of the pad 19. The adjusted position of the pad 19 is not illustrated

in Fig. 3 because its position is obvious and a further showing would merely confuse the figure.

While I have shown and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A garter pad form and hook, comprising a pad of substantially hexagonal shape having both the top and the bottom sides horizontal, a garter support upon the bottom side of said pad, a band attached upon another side of the hexagonal pad and terminating in an eye member at its other end, an isosceles pad having a base side along the side of the hexagonal pad to which said band is attached, a hook fixed upon the vertex opposite the base side of said isosceles pad and capable of coacting with the eye member on the band, and means for adjustably holding said isosceles pad so that its position may be changed wherein its base is at various inclinations to the side of the hexagonal pad which connects with said band, comprising means for pivotally supporting one vertex on the base of said isosceles pad on said hexagonal pad, a bar attached upon said base of the isosceles pad and pivotally mounted at the pivot point of the said isosceles pad, and means for holding the bar in fixed adjusted positions.

2. A garter pad form and hook, comprising a pad of substantially hexagonal shape having both the top and the bottom sides horizontal, a garter support upon the bottom side of said pad, a band attached upon another side of the hexagonal pad and terminating in an eye member at its other end, an isosceles pad having a base side along the side of the hexagonal pad to which said band is attached, a hook fixed upon the vertex opposite the base side of said isosceles pad and capable of coacting with the eye member on the band, and means for adjustably holding said isosceles pad so that its position may be changed wherein its base is at various inclinations to the side of the hexagonal pad which connects with said band, comprising means for pivotally supporting one vertex on the base of said isosceles pad on said hexagonal pad, a bar attached upon said base of the isosceles pad and pivotally mounted at the pivot point of the said isosceles pad, and means for holding the bar in fixed adjusted positions, comprising an eyelet formed at the end of the bar, and means for securing said eyelet upon said hexagonal pad.

3. A garter pad form and hook, comprising a pad of substantially hexagonal shape

having both the top and the bottom sides horizontal, a garter support upon the bottom side of said pad, a band attached upon another side of the hexagonal pad and terminating in an eye member at its other end, an isosceles pad having a base side along the side of the hexagonal pad to which said band is attached, a hook fixed upon the vertex opposite the base side of said isosceles pad and capable of coacting with the eye member on the band, and means for adjustably holding said isosceles pad so that its position may be changed wherein its base is at various inclinations to the side of the hexagonal pad which connects with said band.

4. A garter pad form and hook, comprising a pad of substantially hexagonal shape having both the top and the bottom sides horizontal, a garter support upon the bottom side of said pad, a band attached upon another side of the hexagonal pad and terminating in an eye member at its other end, an isosceles pad having a base side along the side of the hexagonal pad to which said band is attached, a hook fixed upon the vertex opposite the base side of said isosceles pad and capable of coacting with the eye member on the band, and means for adjustably holding said isosceles pad so that its position may be changed wherein its base is at various inclinations to the side of the hexagonal pad which connects with said band, comprising a rivet supported upon the hexagonal pad, a bar pivotally mounted upon said rivet and attached upon the base of said isosceles pad and terminating in an eyelet, and stitches securing said eyelet upon said hexagonal pad.

In testimony whereof I have affixed my signature.
